UNITED STATES PATENT OFFICE.

JAMES ROBERTSON, OF STRATFORD, LONDON, ENGLAND.

ROTARY ENGINE, PUMP, AND THE LIKE.

Application filed March 25, 1920. Serial No. 363,556.

To all whom it may concern:

Be it known that I, JAMES ROBERTSON, a subject of the King of Great Britain, residing at Marsh Gate Engineering Works, 5 Marsh Gate Lane, Stratford, London, England, have invented new and useful Improvements in Rotary Engines, Pumps, and the like, of which the following is a specification.

10 My invention relates to rotary engines, pumps and the like, of the fixed abutment and sliding vane type.

In an engine constructed according to the invention, the rotor is mounted eccentrically 15 within the casing in the usual way, and the motive fluid is supplied axially to the rotor into passages all of which curve backwardly, that is to say, against the direction of rotation, and also expand in width as they pass 20 from the centre to the periphery of the said rotor. The rotor is furnished laterally with radial projections which form radial recesses with portions of the rotor for receiving lugs upon the sliding vanes. The said recesses 25 form a driving engagement between the parts and at the same time permit of the necessary radial movement of the vanes.

Rotary engines and pumps of the above type have before been proposed wherein the 30 motive fluid is supplied axially to the rotor into passages which curve backwards. Others have been provided with radial outwardly expanding passages, and others with two sets of passages, one set being curved 35 backwards and the other set expanding.

As will be understood, the above description applies mutatis mutandis to a rotary pump or blower.

To enable the invention to be fully understood, I will describe the same by reference 40 to the accompanying drawing, in which,

Figure 1 is a sectional side view of a rotary engine constructed according to the invention.

45 Figure 2 is a sectional plan view thereof.

Figure 3 is a section on the line 3-3, Figure 1.

Figure 4 is a sectional side view of the rotor detached.

50 Figure 5 is a plan view thereof.

Figure 6 is a side view of one of the sliding vanes detached, and

Figure 7 is a plan view thereof.

55 *a* indicates the casing of the engine and *b* the rotor which is eccentrically mounted within the casing *a* upon the shaft *c* which

is rotatably carried in bearings *d* in the said casing. *e* is the inlet and *f* the outlet for the motive fluid, each of which is in the form of a curved slot and registers in turn with axial passages *g* having radial portions *h* and formed in the body of the rotor. These passages *h*, as above described, all curve backwards or against the direction of rotation of the rotor *b*, which is indicated by 60 the arrow *i*, and also increase in width as they pass from the centre towards the periphery of the rotor.

j indicates the sliding vanes and *k* the lugs provided thereon. *l* shows the lateral radial projections on the rotor between which and ribs *m* thereon recesses are formed for receiving the lugs *k* on the vanes *j* to form a driving engagement and at the same time permit of the necessary radial movement between these two parts. The vanes are maintained in contact with the inner peripheral face of the casing *a* by centrifugal force.

The vanes *j* in the construction illustrated 80 have the face, which contacts with the inner periphery of the casing *a*, recessed as indicated at *n*, and the recessed portion is placed in communication with the interior of the casing by means of the hole *o*.

The working spaces *p* comprised between 85 each pair of sliding vanes are filled, when at their minimum capacity (shewn at the right hand of Figure 1), with a suitable oil, such as a mineral oil.

The operation of the engine is as follows, 90 that is to say, the motive fluid enters through the inlet *e* and flows through the axial passage *g* into the radial passage *h* at the moment in communication therewith and thence enters the working space into 95 which the said passage opens, and by its expansion in the said space drives the rotor in the direction of the arrow *i* in the usual way. As the rotor rotates the working space is brought into communication with the outlet *f* through which the motive fluid 100 discharges. The centrifugal force generated by the revolving rotor drives the oil contained in each working space *p* outwards to the periphery, of the said space so that 105 the inner surface of the oil layer forms the outer boundary of each effective working space and, as the oil fills the space when the latter is of minimum capacity, that is to say when it is in communication with the outlet passage as shewn on the right hand

85

of Figure 1, the whole of the motive fluid is discharged.

As above described the oil in the working spaces *p* fills the recesses *m* in the sliding vanes *j* through the holes *o* and thereby forms cushions between the said vanes and the inner periphery of the casing *a* and so as to reduce the friction between these surfaces and thus increase the efficiency of the engine.

Although the invention has been particularly described as applied to a rotary engine, it will be understood that it is equally applicable to rotary pumps and blowers.

Claims:

1. A rotary engine, pump or the like of the type referred to, having a rotor provided with radial outwardly expanding passages which are curved backwardly with respect to the direction of rotation of the rotor and the inner ends of which communicate with axial inlet and outlet pas-

sages for the motive fluid, said rotor being provided with recesses, sliding vanes which enter said recesses in the rotor and are furnished with lugs which engage with radial projections on the rotor.

2. A rotary engine consisting of a casing having bearings therein, a recessed rotor eccentrically mounted in said casing upon a shaft, mounted in said bearings, said rotor being provided with radial outwardly expanding passages which are curved backwardly with respect to the direction of rotation of the rotor, and the inner ends of which communicate with axial inlet and outlet passages for the motive fluid, sliding vanes, which enter said recesses in the rotor and are furnished with lugs which engage radial projections on the rotor, and spaces between the pairs of vanes which are adapted to be fitted with a suitable oil to form a cushion between said vanes.

JAMES ROBERTSON.
